AIR CONDITIONING SYSTEM

Clarence W. Nessell, Cleveland, Ohio, assignor to
 Minneapolis-Honeywell Regulator Company,
 Minneapolis, Minn., a corporation of Delaware

Application September 19, 1940, Serial No. 357,359

7 Claims. (Cl. 236—1)

This invention relates to fluid circulating systems, in general, and more particularly to fluid circulating means for warm air heating systems.

In a building having a plurality of spaces or zones to be heated, it is common to provide a warm air furnace connected by ducts to the various zones, and a blower for circulating air through the furnace and the zones. In order to control the temperature in each zone individually, each zone may be provided with a thermostat controlling a motor which operates a damper in the duct leading to the zone, so as to permit or prevent the flow of warm air to the zone in accordance with the air temperature in the zone.

In such a system, it is unnecessary to circulate air as rapidly when one zone is calling for heat as when more than one zone calls for heat. In the present invention, I therefore provide, for a two-zone heating system, means to operate the blower so as to circulate air at one rate when only one zone is demanding heat, to circulate air at a greater rate when two zones demand heat, and also to stop the blower when none of the zones is demanding heat. When none of the zones is demanding heat, there is no need for operation of the blower, since all the zone dampers are closed.

The present invention is an improvement on the system disclosed in my co-pending application No. 161,591, filed August 30, 1937, and issued as Patent No. 2,223,295, dated November 26, 1940. In that application I disclosed a circuit for controlling the speed of a blower in a system having any number of zones. The present invention is a more simplified, less expensive system, which is particularly adapted to control the speed of a blower in a heating system having only two zones.

One of the objects of my invention is to provide improved fluid circulating apparatus for a two-zone air conditioning system.

Another object of the invention is to provide a simple and inexpensive control circuit for a two-speed blower when used in a two-zone air conditioning system.

Other objects of the invention will become apparent upon a study of the following specification and claims and the appended drawing.

The single figure of the drawing represents diagrammatically a two-zone air conditioning system embodying the improved control means of my invention.

A furnace 10 is shown in the drawing and a fan 11 is provided to force the circulation of air through the bonnet of the furnace. Air is dis-

charged through a main duct 12 and smaller delivery ducts 13 and 14 into the zones 15 and 16. A bimetallic thermostat 17 is located in the zone 15 and operates a switch arm 18 between stationary contacts 19 and 20. A similar thermostat 26 is located in zone 16 and operates a switch arm 27 between stationary contacts 28 and 29.

The furnace 10 is shown as of the gas burning type although it may be of any suitable construction. The supply of gas to the main burner 30 of the furnace is controlled by an electrically operated valve 31. Gas is supplied to a pilot burner 32 through a pipe 33 which bypasses the valve 31. A bimetallic safety switch 34 is located adjacent the flame of the pilot burner 32. A thermostat 35 mounted in the bonnet of the furnace operates a fan switch 36 and a limit switch 37 in accordance with the temperature of the air in the bonnet.

The air flowing out of the furnace through the main duct 12 is divided between the smaller ducts 13 and 14. The flow of air through the duct 13 is controlled by a damper 40 which is operated between open and closed positions by a damper motor 41 connected to the damper 40 by any suitable linkage. The damper motor 41 also drives a cam 42 which actuates a switch arm 43. The switch arm 43 is normally biased against a lower contact 44 but may be actuated by the cam to disengage from contact 44 and engage an upper contact 45.

The flow of air through the duct 14 is controlled by a damper 50 similar in all respects to the damper 40 and operated by damper motor 51. The damper motor 51 also operates a cam 52 which controls the position of the switch arm 53. This switch arm 53 is normally biased against a lower contact 54 but may be moved by the cam 52 so as to engage with an upper contact 55.

The connections between cams 42 and 52 and their associated damper motors are such that the cams are rotated through 180 degrees whenever the dampers are rotated through 90 degrees.

A relay 60 is provided which controls the energization of a circuit for the main supply valve 31 and another circuit for the energization of the fan 11. The relay 60 comprises a winding 61 operating two switch arms 62 and 63. When the winding 61 is energized, these switch arms engage stationary contacts 64 and 65, respectively.

The fan 11 is of a type which may be driven at two different speeds and a second relay 66 is provided for controlling the speed at which the

fan is operated. This relay 66 comprises a winding 67 operating a switch arm 68. Switch arm 68 engages a stationary contact 69 when the winding 67 is energized and engages a stationary contact 70 when the winding 67 is deenergized.

Power is supplied to operate this control system through lines 71 and 72. The energizing circuit for the fan 11 may be traced from line 71 through a conductor 73, the fan 11 and thence through either conductor 74 and contact 69 or through conductor 75 and contact 70 to the switch arm 68. The circuit may then be traced from switch arm 68 through a conductor 76, fan controlling switch 36, a conductor 77, contact 65, switch arm 63, and a conductor 78 to the line 72. The internal construction of the motor of fan 11 is such that the fan is operated at a low speed when its energizing circuit is completed through conductor 74 and contact 69, and at a high speed when the circuit is completed through conductor 75 and contact 70.

The main supply valve 31 is energized from a circuit supplied by a transformer 79 having a primary winding 80 connected to the supply lines 71 and 72 and a secondary winding 81. This circuit may be traced from the left-hand end of secondary winding 81, as it appears in the drawing, through conductors 82 and 83, switch arm 62, contact 64, conductor 84, limit switch 37, a conductor 85, safety switch 34, a conductor 86, main supply valve 31, and conductors 87, 88, and 89 to the right-hand terminal of secondary winding 81.

The energization of relay 60 is controlled by a circuit which extends from the left-hand end of secondary winding 81 through conductors 82 and 83, relay winding 61, and then either through conductor 90, switch contact 45, switch arm 43 and conductors 87 and 88 or through conductor 91, contact 55 and switch arm 53 to conductor 89 and thence to the right-hand end of transformer winding 81.

The energization of relay winding 66 is controlled by a circuit which may be traced from the left-hand end of secondary winding 81 through conductors 82 and 83, relay winding 67, and then either through a conductor 92, contact 44, switch arm 43, and conductors 87 and 88, or through a conductor 93, contact 54, and switch arm 53 to conductor 89 and thence to the right-hand end of secondary winding 81.

It will be seen, therefore, that relay winding 61 is energized whenever either of switch arms 43 and 53 engages its associated upper contact, and that relay winding 67 is energized whenever either of switch arms 43 and 53 engages its lower contact.

The damper motors 41 and 51 are energized from the transformer secondary winding 81 through lines 82, 88, and 89. These damper motors are controlled respectively by the zone thermostats 17 and 26. Contacts 19 and 20 of thermostat 17 are connected to damper motor 41 by conductors 100 and 101, respectively. The bimetallic element of thermostat 17 is also connected to damper motor 41 through a conductor 102. The thermostat 26 is similarly connected to damper motor 51 through conductors 103, 104, and 105. Both the thermostats are constructed so as to move their switch arms against the left-hand contact when the temperature within the zone drops below the value which it is desired to maintain and move their switch arms against the right-hand contacts when the temperature

rises above the desired value. This mode of operation is indicated by the legend appearing above the thermostats in the drawing. These damper motors may be of a conventional type, in which, upon engagement of the thermostatic switch with its cold contact, for example, the damper motor moves its associated damper from closed to open position. As the damper reaches open position, the motor energizing circuit through the cold contact is broken, and contacts are closed which will permit the motor to be energized through the hot contact of the thermostat in order to move the damper back to its closed position.

Operation

When the parts are in the positions shown in the drawing the thermostat 17 is calling for heat. As a consequence a circuit has been completed through conductor 100, contact 19 and switch arm 18, bimetallic element 17 and conductor 102 which has energized damper motor 41 so that damper 40 has been moved to its open position and cam 42 has moved switch arm 43 into engagement with contact 45.

The engagement of the switch arm 43 with contact 45 completes an energizing circuit for the relay 60 and consequently moves the switch arms 62 and 63 into engagement with their respective contacts 64 and 65. The closure of switch arm 62 on contact 64 completes a circuit previously traced through the main supply valve 31 so that fuel is supplied to the furnace. Of course, if this circuit is broken by the safety switch 34 due to failure of the pilot flame or by the limit switch 37 due to the presence of an excessive temperature in the bonnet of the furnace, this energizing circuit will not be completed. Assuming that conditions in the furnace are normal, however, the main supply valve 31 will be opened and fuel will be ignited at the main burner 30.

The temperature in the bonnet of the furnace will then rise causing the thermostat 35 to close the fan switch 36, thus completing an energizing circuit for the fan 11. The relay 66 is energized at this time since switch arm 53 is closed on contact 54. The switch arm 68 is therefore held in its attracted position against the contact 69 so that the fan is energized through contact 69 and conductor 78. This results in the operation of the fan at its low speed.

If the thermostat 26 should now move its switch arm 27 against the contact 28, thus calling for heat, a circuit would be completed to the damper motor 51 which would cause the motor to move the damper 50 through 90 degrees and the cam 52 through 180 degrees. This would open the damper 50 to admit air to the zone 16. Operation of the cam 52 through 180 degrees would cause the switch arm 53 to be moved away from the contact 54 resulting in the deenergization of relay winding 67. The switch arm 68 would thereupon fall to its lower position, thus opening the low speed fan circuit through contact 59 and closing the high speed fan circuit through contact 70.

This operation would continue until one of the thermostats became satisfied, whereupon its associated switch arm would be moved to the right completing a circuit which would energize the damper motor to return the damper to its closed position and at the same time move the cam so as to permit the cam operated switch to move against its lower contact. This would complete an energizing circuit for the relay 66, thus lift-

ing the switch arm 68 against contact 69 and returning the fan to low speed operation.

It should be apparent to those skilled in the art that this system might be applied to the operation of a two speed fan in a heating system having more than two zones. In such a system, however, the fan would never reach its highest speed of operation until all the zones called for heat simultaneously. The utility of this system is therefore peculiarly adapted to two zone requirements.

While I have shown and described a specific embodiment of my invention, it should be understood that I am to be limited only by the scope of the appended claims.

I claim as my invention:

1. In a system for conditioning the air in two zones, in combination, air conditioning means, ducts for conveying conditioned air from said means to said zones, damper means in said ducts for individually controlling the delivery of air to each zone, separate motor means for operating the damper means of each zone, means in each zone responsive to a condition indicative of the need for a supply of conditioned air for controlling the operation of said motor means, means for circulating air through said conditioning means and ducts to said zones at two different rates of flow, a first relay controlling the energization of said circulating means, a second relay controlling the rate of flow at which said circulating means is operated, a single-pole, double-throw switch associated with each said damper means and operated simultaneously therewith by said motor means, a first contact for each said switch with which it engages when said dampers are open, a second contact for each switch with which it engages when said dampers are closed, an energizing circuit for said first relay including said switches and said first contacts in parallel, and an energizing circuit for said second relay including said switches and said second contacts in parallel.

2. In a system for heating the air in two zones, in combination, a heater, ducts for conveying heated air from said heater to said zones, damper means in said ducts for individually controlling the delivery of air to each zone, separate motor means for operating the damper means of each zone, a thermostat in each zone for controlling the operation of said motor means, means for circulating air from said heater to said zones at two different rates of flow, a first relay controlling the energization of said circulating means, a second relay controlling the rate of flow at which said circulating means is operated, a single-pole, double-throw switch associated with each said damper means and operated simultaneously therewith by said motor means, a first contact for each said switch with which it engages when said dampers are open, a second contact for each switch with which it engages when said dampers are closed, an energizing circuit for said first relay including said switches and said first contacts in parallel, and an energizing circuit for said second relay including said switches and said second contacts in parallel, said second relay when energized due to closure of any of said damper means permitting operation of said circulating means only at the lower of said two rates of flow, and when deenergized due to opening of all said damper means permitting operation of said circulating means only at the higher of said two rates of flow.

3. In a system for heating the air in two zones,

in combination, a heater, ducts for conveying heated air from said heater to said zones, damper means in said ducts for individually controlling the delivery of air to each zone, separate motor means for operating the damper means of each zone, a thermostat in each zone for controlling the operation of said motor means, means for circulating air from said heater to said zones at two different rates of flow, a first relay controlling the energization of said circulating means, a second relay controlling the rate of flow at which said circulating means is operated, switch means associated with each said damper means and operated by said motor means so as to assume a first position when said damper means is open and a second position when said damper means is closed, an energizing circuit for said first relay including any of said switch means which is in its first position, and an energizing circuit for said second relay including any of said switch means which is in its second position.

4. In a system for conditioning the air in two zones, in combination, air conditioning means, ducts for conveying conditioned air from said means to said zones, damper means in said ducts for individually controlling the delivery of air to each zone, separate motor means for operating the damper means of each zone, means in each zone responsive to a condition indicative of the need for a supply of conditioned air for controlling the operation of said motor means, means for circulating air through said conditioning means and ducts to said zones at two different rates of flow, a first relay controlling the energization of said circulating means, a second relay controlling the rate of flow at which said circulating means is operated, said first relay when energized permitting energization of said circulating means and when deenergized preventing energization of said circulating means, said second relay when energized permitting operation of said circulating means at the lower of said two rates of flow, and when deenergized permitting operation of said circulating means at the higher of said two rates of flow, and switch means responsive to the positions of said damper means for completing an energizing circuit for said first relay when any of said damper means is open and for completing an energizing circuit for said second relay when any of said damper means is closed.

5. In a system for conditioning the air in two zones, in combination, air conditioning means, ducts for conveying conditioned air from said means to said zones, damper means in said ducts for individually controlling the delivery of air to each zone, separate motor means for operating the damper means of each zone, means in each zone responsive to a condition indicative of the need for a supply of conditioned air for controlling the operation of said motor means, means for circulating air through said conditioning means and ducts to said zones at two different rates of flow, a first relay controlling the energization of said circulating means, a second relay controlling the rate of flow at which said circulating means is operated, said first relay when energized permitting energization of said circulating means and when deenergized preventing energization of said circulating means, switch means associated with each said damper means and operated by said motor means so as to assume a first position when said damper means is open and a second position when said damper means is closed, an energizing circuit for said

first relay including any of said switch means which is in its first position, and an energizing circuit for said second relay including any of said switch means which is in its second position.

6. In a system for conditioning the air in a plurality of zones, in combination, air conditioning means, ducts for conveying conditioned air from said means to said zones, damper means in said ducts for individually controlling the delivery of air to each zone, separate motor means for operating the damper means of each zone, means in each zone responsive to a condition indicative of the need for a supply of conditioned air for controlling the operation of said motor means, means for circulating air through said conditioning means and ducts to said zones at two different rates of flow, a first relay controlling the energization of said circulating means and said air conditioning means, said relay when energized permitting energization of said two means, and when deenergized preventing energization of said two means, a second relay controlling the rate of flow at which said circulating means is operated, and switch means responsive to the positions of said damper means for completing an energizing circuit for said first relay when any of said damper means is open, and for controlling energization of said second relay in accordance with the number of said damper means which is open.

7. In a system for conditioning the air in a

30
plurality of zones, in combination, air conditioning means, ducts for conveying conditioned air from said means to said zones, damper means in said ducts for individually controlling the delivery of air to each zone, separate motor means for operating the damper means of each zone, means in each zone responsive to a condition indicative of the need for a supply of conditioned air for controlling the operation of said motor means, means for circulating air through said conditioning means and ducts to said zones at two different rates of flow, a first relay controlling the energization of said circulating means and said air conditioning means, said relay when energized permitting energization of said two means, and when deenergized preventing energization of said two means, a second relay controlling the rate of flow at which said circulating means is operated, said second relay when energized permitting operation of said circulating means at the lower of said two rates of flow, and when deenergized permitting operation of said circulating means at the higher of said two rates of flow, and switch means responsive to the positions of said damper means for completing an energizing circuit for said first relay when any of said damper means is open and for completing an energizing circuit for said second relay when any of said damper means is closed.

CLARENCE W. NESSELL.
